CLAIM

The ornamental design for a portable tool stand, as shown and described.

DESCRIPTION

FIG. 1 is a perspective view of the portable tool stand of the present invention, with broken lines depicting a bench top tool for illustrative purposes only and which form no part of the claimed design.

FIG. 2 is a front elevation view of the portable tool stand of the present invention.

FIG. 3 is a top view of the portable tool stand of the present invention.

FIG. 4 is an end view of the portable tool stand of the present invention, the opposite end being a mirror image thereof; and,

FIG. 5 is a rear elevation view of the portable tool stand of the present invention.
